UNITED STATES PATENT OFFICE.

CHARLES J. COOKE, OF WASHINGTON, DISTRICT OF COLUMBIA, AND JOHN A. RENNIE, OF NEW YORK, N. Y., ASSIGNORS TO CHARLES E. SHEPPARD, OF LONG ISLAND CITY, NEW YORK.

REPEATING ATTACHMENT FOR SOUND-REPRODUCING MACHINES.

Application filed September 25, 1923. Serial No. 664,740.

Our invention relates to record repeating attachments for sound reproducing machines, and has for an object simplification of and certain structural improvements upon 5 the repeating attachment for phonographs represented by U. S. Letters Patent No. 1,373,382, issued March 29, 1921, to Charles John Cooke, one of the present joint applicants.

10 The present invention has for a further object the production of a self-contained attachment of the character indicated, capable of automatically repeating a musical or other record, indefinitely, within the range 15 of the motor employed, and practically without interruption.

Sound reproducing machines such as vintrolas, graphophones, phonographs and like instruments are extensively employed for 20 the purpose of producing dance music, and in this use obviously, it is desirable to repeat the selection continuously without the interruption incident to replacing the reproducing needle by hand.

25 A further object of the present invention is the production of an extremely simple, inexpensive, and efficient attachment of the character indicated, arranged and adapted to automatically lift the sound-box or reproducer each time its needle reaches the 30 end of a record, instantly and automatically return same to its starting point, and thereupon lower said needle into operative engagement with the record-groove, practically 35 without interruption.

A further object is the production of means whereby the sound-box is automatically replaced, or reset as aforesaid, by agency of needle-engaging mechanism.

40 Another object of the present invention is the production of repeating attachments capable of instant and easy application to sound reproducing machines of the disk-record type, without the employment of attaching tools of any description, and without the possibility of incorrect application.

45 The present invention further consists in certain novel features of construction, and in the arrangement and combination of parts 50 hereinafter described and more particularly pointed out by the claims following.

In the accompanying drawings which form part of this application for Letters Patent, and whereon like characters indi-

cate corresponding parts in the several views:

Figure 1 is a top plan view in normal position, of our present invention applied in operative relation to the face of a sound-reproducing record of disk form, the latter 60 broken away for economy of space upon the sheet;

Figure 2 is also a top plan view corresponding with Figure 1, except that here the reproducing needle has been automatically projected to its outermost or starting point upon the record;

Figure 3 is a side elevation of the invention in normal position;

Figure 4 is a relatively enlarged fragmentary view taken upon line 4—4 of Figure 1, showing in longitudinal vertical and central section the pivotal connection of the operating arm;

Figure 5 is also an enlarged fragmentary view of parts represented by Figure 4;

Figure 6 is a fragmentary perspective view of an ordinary reproducing needle, engaged by the pick-up end of the improved operating arm;

Figure 7 is a view corresponding with Figure 6 but at right angles thereto, being taken on the line 7—7 of said Figure 6; and

Figure 8 is a vertical central section through the spring retained hollow attaching boss.

Reference being had to the drawings and characters thereon, A indicates the upper, pointed and protruding end of an ordinary driving shaft, under control of a motor, not shown, B indicates a circular disk record impaled centrally upon said shaft A in the ordinary and well understood manner, C the usual needle socket depending from a sound-box (not shown), and D a reproducing 95 needle carried by said socket as usual.

The numeral 10 indicates the base-plate or turntable of the present invention formed preferably of relatively thin metal, its exact outline or configuration being immaterial. 100 This base plate is perforated as at 11, and is there provided with a rigid upstanding hollow thimble 12 as best shown by Figure 8 of the drawings.

Within the thimble 12 as by means of a 105 drive fit is rigidly secured the upper thickened end of a tubular barrel-spring 13 slotted longitudinally at diametrically op-

posite points as at 14, thus providing for a degree of radial expansion and contraction, or spring action, whereby the entire base 10 is removably but firmly retained by frictional engagement upon the driving shaft A, and in contact with the central upper surface of a record B as shown.

Rotatably mounted in the base plate 10 near one end, and adjacent the attaching 10 thimble 12, is a shouldered pivot or stud 15 which is retained in position by means of riveting said stud 15 over washer 16 as at 17 in underside of base. This pivot stud 15 has an enlarged head 18, which offsets a coil 15 spring 19 by which the said stud is surrounded as shown by Figures 3, 4, and 5, and for purposes that will later appear.

As best shown by Figure 4, the said stud 15 is surrounded at its base by a boss pressed 20 out of and integral with base 10, and serving as a shoulder upon which stud 15 freely rotates. A pressed cam surface 20 is concentric with stud 15, and its ends 21 and 22 are bevelled as shown.

25 The upper end or head of the stud 15 is provided with a horizontal through-slot 23 slightly elongated to receive a transverse trunnion pin 24, the opposite ends of which find bearings in down-turned flanges 25, 25, 30 of an actuating arm 26.

This actuating arm is provided with a down-turned cam-engaging projection or tongue 27 arranged and adapted to travel over the cam track 20, and to raise or lower 35 the arm 26 when occasion requires, as it ascends or descends the bevelled edges or inclines 21 or 22, respectively.

At its outer end the said actuating arm 40 is provided with integral picking fingers 28 separated by a V-groove 29 for contacting with and picking up a reproducing needle at predetermined intervals as will appear in a description of operation.

The coil spring 19, hereinbefore referred 45 to, is anchored at one end 30 in a small hole sunk into the surface of base-plate 10, and at its opposite end 31 angles sharply through the root of tongue 27, in which position it serves the two-fold purpose of always returning arm 26 to its normal position against thimble 12 serving as a fixed stop therefor, and of normally, but yieldingly advancing 50 the horizontal trunnions 24 to the forward end of their supporting slot 23 in the rotatable stud 15.

When constructed and arranged substantially as exemplified by the present drawings, the use and operation of our improved repeating attachment is as follows:

60 A musical or other disk record having first been positioned as usual, our improved self-contained attachment is applied by introducing the hollow thimble 12 over the protruding end of drive shaft A, which is thereupon gripped by the spring jaws of

tubular barrel 13 in frictional contact with the under surface of base-plate 10 resting squarely upon the central ungrooved portion of record B, as indicated by Figures 1 and 3.

In this normal relation of parts, the motor (not shown) is started, and the reproducing needle or stylus D is lowered into engagement with a groove near the outer edge of the record as in the ordinary use of such reproducing instruments, our improved attachment in the meantime, rotating bodily and concentrically with disk B around the central drive shaft A.

Gradually approaching the center of record B the needle D is finally led directly 80 into the V-groove 29 between picking fingers 28-28, thus retarding the distal end of actuating arm 26. At the same time the continued rotation of base 10 moves incline 21 beneath the lowermost rounded end of tongue 27 to quickly elevate the outer end of arm 26, and with it the needle socket C and needle D clear of the record B. The reproducing needle is thus maintained in an elevated position while base 10 is rotated to the position indicated by Figure 2 of the drawings, tongue 27 riding over the surface of cam plate 20, until its incline 22 is reached down which latter it descends, at the instant the arm 26 reaches its extreme outermost position as shown by 90 Figure 2.

The descent of tongue 27 as aforesaid causes needle D to correspondingly descend in its reset position at beginning of the record, whereupon further rotation of base 10 causes the arm 26 to drag past the reproducing needle, and then return instantly under action of spring 19, to its normal position as shown by Figure 1, the thimble 12 serving as a stop.

The foregoing operation may then be repeated indefinitely and automatically, the pick-up fingers 28 engaging needle D to elevate and replace the same, each time the latter is brought within reach of said revolving fingers.

When in the course of the record rotation, and the regular advance, or feeding in, of needle D, the pitch and character of the record groove is such that the outer finger 28 reaches well beyond the center of needle D as shown by Figure 7, the replacing or resetting process instantly takes place; but on the other hand when the character of the record groove is such that the feed of the reproducer needle causes the outer finger 28 to strike short of the center of said needle, one of two results must follow, either the needle will be caused to cut over into the preceding groove thus injuring the record, or said finger 28 must be capable of yielding so that it may brush past needle D for another complete rotation. In practice the latter is what happens, and the advance finger 28 slips to one side or the other of

needle D. If to the far side the repeater functions at once; if to the near side the entire arm 26 yields, and as the outermost pick-up finger 28 brushes past the body of 5 needle D the said arm 26 is reciprocated longitudinally on its trunnions 24 the length of slot 23, this being sufficient to permit passing needle D which is picked up on the 10 next round of the fingers 28, to be thus again returned to the starting point.

Upon the face of base plate 10 a blank line 32 and two oppositely positioned arrows 33 are stamped as a means of indicating the correct extension of needle D from its socket 15 C, in accordance with the normal height of arm 26 and its pick-up fingers 28; and, it will be noted that engagement of the said fingers 28 with needle D causes the former to travel up the latter as a guide, until arrested beneath the under surface of socket C which is thereupon lifted bodily carrying with it the reproducing needle.

The foregoing being a description of our present invention in one approved form of construction, it will be understood that the parts herein shown and described may be variously modified, altered and rearranged without in the least departing from the spirit of the invention involved, so long as substantially the same results are accomplished, and to all such modifications we lay claim the same as if herein set forth and described.

Having thus described our invention in one complete and operative form of embodiment what we now claim and desire to secure by Letters Patent is:

1. In a repeating attachment for sound reproducing machines, the combination with a supporting base, of an actuating arm pivoted eccentrically upon said base, means cooperating with said arm for causing its free end to engage a reproducing needle to lift and return the same to its starting point, and a hollow thimble having a split tubular lining of spring material and of downwardly converging form permanently driven into said thimble for holding the attachment in operative position.

2. In a repeating attachment for sound reproducing machines, the combination with a supporting base, of an actuating arm pivoted eccentrically upon said base, means cooperating with said arm for causing its free end to engage a reproducing needle to lift and return the same to its starting point, and a hollow thimble, having a split tubular lining of spring material and of downwardly converging form permanently driven into said thimble for holding the attachment in operative position, serving also as a stop for said arm, and a spring for returning said arm to normal position after each operation.

3. In a repeating attachment for sound reproducing machines, the combination with

a supporting base, of an actuating arm pivoted eccentrically upon said base, pick-up fingers raised above the distal end of said arm, means cooperating with the actuating arm for causing its said fingers to engage, 70 lift and return a reproducing needle to its starting point, and a hollow thimble having a split tubular lining of spring material and of downwardly converging form permanently driven into said thimble for holding 75 the attachment in operative position.

4. In a repeating attachment for sound reproducing machines, the combination with a supporting base, of an actuating arm pivoted eccentrically upon said base, means cooperating with said arm for causing its free end to engage a reproducing needle to lift and return the same to its starting point, and a hollow thimble having a radially split expandible tubular lining arranged and 80 adapted to secure the attachment in operative position.

5. In a repeating attachment for sound reproducing machines, the combination with a supporting base, of a stud pivoted eccentrically upon said base, a vertically movable actuating arm pivoted upon said stud, means for permitting slight longitudinal movement of the actuating arm relative to said stud, means cooperating with said arm for causing its free end to engage, lift and return a reproducing needle to its starting point, and a hollow spring-retained thimble for securing the attachment in operative position.

6. In a repeating attachment for sound reproducing machines, the combination with a supporting base, of an actuating arm pivoted eccentrically upon said base, means carried by said arm for engaging and lifting a reproducing needle, means for returning 100 said needle to a starting point, a split hollow tubular spring retaining-thimble for securely holding the attachment in operative position, and a coil spring for yieldingly holding said actuating arm in its normally 105 advanced position and for returning it into engagement with the thimble aforesaid after each needle replacement.

7. In a repeating attachment for sound reproducing machines, the combination with 115 a supporting base, of an actuating arm pivoted eccentrically upon said base, means for permitting said arm to yield slightly in a longitudinal direction, and means cooperating with said arm for causing its outer end 120 to engage, lift and return a reproducing needle to its starting point, whereby in the event of incomplete engagement of the reproducing needle the arm will automatically 125 pass the latter for further rotation with the record.

In testimony whereof we affix our signatures.

CHARLES J. COOKE.
JOHN A. RENNIE.
